UNITED STATES PATENT OFFICE

PETER KRÜCKEN, OF MANNHEIM-FEUDENHEIM, GERMANY

MACHINE AND METHOD FOR TREATING CIGARS

Application filed January 17, 1930. Serial No. 421,553.

My invention relates to a method of and a machine for treating cigars.

With the consumption of cigars the peculiar feature exists of smokers preferring cigars and also the so-called cigarillos that have a dull grey color. Now, as those wrappers which do not possess this preferred grey appearance are comparatively costly and their price increases with increased demand, my invention has for its object to so treat cigars the wrappers of which originally do not possess this preferred grey appearance, that they answer to the demand and taste of the public. To this end my invention has for its object a method and a machine which enables to give cigars or cigarillos that originally have a bright wrapper of fatty appearance the desired dull grey color by applying thereon impalpably fine powdered pure tobacco, so-called tobacco powder. The progress and advantage afforded by my present method and machine resides in the fact that the treatment of the cigars, first and foremost the application of the powder layer is effected very quickly and easily and in so fine a degree that the tobacco powder itself cannot be detected with the naked eye and the cigars are not injured.

My invention comprises a new construction and combination of mechanical members and other peculiar details as described hereinafter in detail and illustrated in the accompanying drawing which shows a vertical section through a power-driven powdering machine designed in accordance with my invention.

The housing of the machine is made from wood or any other suitable material and has a straight rear wall *a*, an inclined front wall *b* and two side walls *c*. The latter have mounted on them shafts *d* and *e* that carry the powdering cylinders *d*¹, *e*¹ which are fitted with a coating of a very soft material such as spongy rubber. The powdering cylinders co-operate with correspondingly curved counter faces *f*, *g* likewise coated with spongy rubber or the like, the rubber cover being fixed on suitable plate-shaped carriers *f*¹, *g*¹ by means of a binder, such as a suitable glue. The carriers *f*¹, *g*¹ in their

turn are fixed on to the lateral walls *c* by screws or in any other suitable manner. The carrier *f*¹ subsides into a perforated inclined chute *f*² above which is arranged a finishing brush cylinder *h* made from goat's hair or any other suitable material. 55

The function of this machine is as follows:

An electric motor *J* lodged in the under-frame of the machine and having its shaft projecting through a hole of one of the lateral walls *c*, drives by cord and pulley the powdering cylinders *d*¹, *e*¹ and finishing cylinder *h* in the manner clearly to be seen from the drawing, and, further, a feeding conveyer *i* and issuing conveyer *k*. Above the powdering cylinder *e*¹ is arranged a box *m* having a perforated bottom and containing the tobacco powder. This box can rock about a pin *m*¹ and is periodically lifted by means of a shaking member *n* and then let drop, so that the powdering cylinder *e*¹ and the cigars that enter at *A* are powdered. When passing between the two spongy rubber layers *e*¹, *g* the tobacco powder is applied on the 70 cigars the first time, because there is only a quite small air gap between these two rubber layers, the softness of the rubber protecting the cigars passing therethrough from being injured in any way. 80

The described powdering process is repeated on the spongy rubber layers *d*², *f*, the tobacco powder in excess falling off in part while the cigars glide on the chute *f*² and collects in a drawer *p*. A complete removal of 85 the powder in excess, so that the powder particles cannot be detected by the naked eye and on the tongue, is effected by the goat's hair brush cylinder *h*. The finished cigars leave the machine on the issuing conveyer *k* 90 from which they are withdrawn, this conveyer being likewise driven by the motor *J*. In order to remove from this conveyer *k* tobacco powder that happens to adhere thereto another brush cylinder *q* is arranged 95 the action of which is clearly to be seen from the drawing. Any escapement of the tobacco powder which is highly volatile through the outlet passage *k*¹ is prevented by a trap door *r* the frontal wall *r*¹ of which is made of soft 100

cloth. The regulation of the quantity of tobacco powder to be delivered by the box *m* is effected by means of a set cam *s¹* mounted on a pin *s*. As to be seen, the altitude of fall of box *m* varies according to the adjustment of cam *s¹*.

I wish to be understood that without deviating from the essence of the invention, the manner of drive, the design of the conveyers and of the powder box can vary so as to meet the varying working conditions to be met.

What I claim and desire to secure by Letters Patent, is:—

1. A machine for powdering cigars comprising in combination rotary powder-applying cylinder having a coating of soft material, a fixed curved counter face coated with the same material and adapted to co-operate with said cylinder, a feeding conveyer and an issuing conveyer for the cigars, a perforated chute adapted to transfer the cigars from said cylinder to said issuing conveyer, a brush cylinder arranged above said chute and adapted to act upon the cigars thereon, means for powdering said powder-applying cylinder, and means for driving said cylinders and conveyers.

2. A machine for powdering cigars comprising in combination two successive rotary powder-applying cylinders having a coating of soft material, two fixed counter faces fitted with the same material and arranged for co-operation with and opposite said cylinders so that a gap is formed therebetween through which the cigars may be engaged, a feeding conveyer and an issuing conveyer for the cigars, a perforated chute adapted to transfer the cigars from said gap to said issuing conveyer, a brush cylinder arranged above said chute and adapted to act upon the cigars thereon, a powder box arranged above one of said powder-applying cylinders and adapted to feed powder to it, and mechanical means for driving said cylinders and conveyers and for imparting a shaking motion to said powder box.

3. A machine for powdering cigars comprising in combination two successive rotary powder-applying cylinders having a coating of spongy rubber, counter-faces curved in correspondence to said cylinders and having likewise a coating of spongy rubber, a cigar feeding conveyer and a cigar issuing conveyer, a shaking powder box adapted to powder the first of said cylinders and the appurtenant counter face, a chute adapted to transfer the cigars from the second cylinder to said issuing conveyer, a rotary brush arranged above the chute and adapted to act upon the cigars thereon, another rotary brush arranged below said issuing conveyer and adapted to act thereupon, a housing enclosing said box, cylinders and counter faces, said conveyers projecting with their outer ends beyond said housing, a cloth trap door

on said housing at the passage of said issuing conveyer, an electric motor and means for driving all said movable members of the machine from the latter.

In testimony whereof I affix my signature. 70

PETER KRÜCKEN.
